ASYMMETRICAL UREA DISAZO DYESTUFFS

Otto Kaiser, Basel, Switzerland, assignor to the Swiss firm of Society of Chemical Industry in Basle, Basel, Switzerland

No Drawing. Application April 20, 1943, Serial No. 483,801. In Switzerland June 20, 1942

7 Claims. (Cl. 260—175)

In U. S. patent application Serial No. 434,009, filed March 9, 1942, (now U. S. Patent No. 2,341,791), there are described new disazo-dyestuffs of the general formula

in which R stands for the radical of a sulfosalicylic acid, R₁ and R₃ stand for aromatic nuclei of the benzene series wherein the —N=N— and the

groups stand in 1:4-position to one another, R₂ stands for an aromatic nucleus of the benzene series, in which the

and the

groups stand in another position than in the 1:2-position to one another, and R₄ stands for an aromatic nucleus of the benzene series containing an OH— group and a carboxyl group in ortho-position to this OH— group.

These dyestuffs which are monosulfonic acids of definite asymmetrical urea-like disazo-dyestuffs, represent valuable direct dyeing dyestuffs which are characterized by the strength of the dyeings produced with their aid and by the very good wet fastness properties of these dyeings after-treated with agents yielding copper.

It has been found that not only the urea-like disazo-dyestuffs possess these valuable properties, but that they are inherent quite generally in the monosulfonic acids of the asymmetrical ureas of the general formula

wherein R and R₄ stand for aromatic nuclei of the benzene series containing an OH— group and a carboxyl group in ortho-position to this OH— group, one of the two x's stands for a —N=N— group and the other for a

group, R₁, R₂ and R₃ stand for aromatic nuclei of the benzene series, wherein any

groups attached to one and the same benzene

nucleus stand in 1:4-position to one another, —N=N— and

groups attached to one and the same benzene nucleus stand also in 1:4-position to one another, the

groups and —N=N— or

groups attached to one and the same benzene nucleus stand however in another position than in 1:2-position to one another, and R is always linked directly to a nitrogen atom of the connecting member x, and wherein finally that benzene nucleus which is linked directly to the

group is free from sulfonic groups and R is also free from sulfonic groups if the CO— group is linked directly to the radical R₂.

The new dyestuffs are obtained by the methods usual for such products. In accordance with the foregoing data, the components for the various methods which are described further below should be so selected that the final dyestuff contains only one sulfonic group, those benzene nuclei which are linked directly to the CO— group carrying no sulfonic groups and R being also free from sulfonic groups if the CO— group is linked directly to the radical R₂.

The new dyestuffs can be made for example by combining 1 mol of an azo-dyestuff of the general formula

in which R, x, R₁ and R₂ have the meanings above given, with 1 mol of an azo-dyestuff of the general formula

in which R₄ and R₃ have the aforesaid meanings by treatment with phosgene to produce the corresponding urea derivative.

Another method consists in diazotizing 1 mol of an aminoazo-dyestuff of the general formula

in which R, R₁, R₂, R₃ and x have the meanings in-

dicated above, or 1 mol of such an aminoazo-dye-stuff of the general formula

in which R_1 , R_2 , R_3 and R_4 have also the aforesaid meanings and x stands for a

group, and coupling with an ortho-hydroxy-carboxylic acid of the benzene series.

A further method of making the new dye-stuffs consists in tetrazotizing asymmetrical ureas of the general formula

wherein K, B₁ and B₂ stand for aromatic nuclei of the benzene series and y stands for a

group,

and $-\text{NH}_2$ - groups standing in 1:4-position to one another and

and

or $-\text{NH}_2$ — groups standing in another position than in 1:2-position to one another, and coupling them with 2 mols of the same or different ortho-hydroxycarboxylic acids of the benzene series.

Products corresponding to the above explained general formula

are for example compounds such as 4-hydroxy-1:1'-azobenzene-4'-(4''-amino-2''-sulfo)-carboxylamino-benzene-3-carboxylic acid, 4'-(3''-amino)-benzoylamino-1:1'-azobenzene-4-hydroxy-2'-sulfo-5-carboxylic acid, and the like.

boylaminobenzene, 4-amino-2-methyl-1:1'-azobenzene-3'-(4''-hydroxy-3''-carboxy)-carboylaminobenzene, 4-amino-2-methyl-5-methoxy-1:1'-azobenzene-3'-(4''-hydroxy-3''-carboxy)-carboylaminobenzene, 4-amino-2-methyl-1:1'-azobenzene-4'-(4''-hydroxy-3''-carboxy-5''-sulfo)-carboylaminobenzene, 4-amino-2-methyl-1:1'-azobenzene-4'-(4''-hydroxy-3''-carboxy-6''-sulfo)-carboylaminobenzene, 4-amino-2-methyl-1:1'-azobenzene-4'-(2''-hydroxy-3''-carboxy-5''-sulfo)-carboylaminobenzene, 4-amino-2-methyl-5-methoxy-1:1'-azobenzene-3'-(2''-hydroxy-3''-carboxy-5''-sulfo)-carboylaminobenzene and the like.

15. Products which may correspond for example to the above explained general formula.

are for example 4'-amino-1:1'-azobenzene-4-hydroxy-3-carboxylic acid, 4'-amino-2'-methyl-1:1'-azobenzene-4-hydroxy-3-carboxylic acid, 4'-amino-5'-methoxy-2'-methyl-1:1'-azobenzene-4-hydroxy-3-carboxylic acid, 4'-amino-3'-methoxy-4-hydroxy-1:1'-azobenzene-3-carboxylic acid, 4'-amino-3'-methyl-4-hydroxy-1:1'-azobenzene-3-carboxylic acid and the like.

As asymmetrical ureas of the above explained general formula

there may be further used: products such as 4-amino-4'-(4"-amino)-benzoylamino-diphenylurea-3-sulfonic acid, 4-amino-4'-(4"-amino-3"-sulfo)-benzoylamino-diphenylurea, 4-amino-3'-(4"-amino)-carboylaminobenzene-diphenylurea, 4-amino-4'-(4"-amino)-carboylaminobenzene-diphenylurea, 4-amino-3'-(4"-amino)-carboylaminobenzene-diphenylurea-3-sulfonic acid, 4-amino-3'-(4"-amino-3"-sulfo)-carboylaminodiphenylurea, 4-amino-4'-(4"-amino-3"-sulfo)-carboylaminodiphenylurea, and the like.

The following examples illustrate the invention, but are not to be regarded as limiting it in any way, the parts being by weight:

Example 1

33.7 parts of the saponified monoazo-dyestuff from diazotized 1-amino-4-acetylaminobenzene-2-sulfonic acid and 1-hydroxybenzene-2-carboxylic acid are dissolved as sodium salt in 250 parts of water with addition of 13.5 parts of sodium acetate. This solution is treated at about 60° C. with 18.5 parts of 3-nitro-benzoylchloride which have been mixed with 5 parts of acetone. The nitrobenzoyl product which has been formed is reduced at 65-70° C. with 42 parts of crystallized sodium sulfide dissolved in 75 parts of water, to the aminobenzoyl product.

45.6 parts of the precipitated reduction product are dissolved in 3000 parts of water with 25.7 parts of 4-amino-4'-hydroxy-1:1'-azobenzene-3'-carboxylic acid with addition of sodium carbonate until the reaction is distinctly alkaline, and the whole is treated with phosgene for 20 hours at 30-40° C., while stirring, until a free NH₂- group can no longer be detected. The formed urea derivative is precipitated as sodium salt, filtered and dried. The new dyestuff which corresponds to the formula

represents a yellow brown powder and dyes cotton in a feebly alkaline bath mixed with a copper salt solution from copper sulfate and sodium tartrate, greenish yellow tints which are fast to washing.

The dyestuffs obtained by replacing the 1-hydroxybenzene-2-carboxylic acid mentioned in the first paragraph of this example by the 1-hydroxy-6- or -5-methylbenzene-2-carboxylic acid, or by replacing the 3-nitrobenzoylchloride

dissolved in 3000 parts of water with 38.1 parts of 4'-amino-1:1'-azobenzene-2'-methyl-5'-methoxy-4-hydroxy-3-carboxylic acid with addition of sodium carbonate until the reaction is distinctly alkaline, and the whole is treated with phosgene for 20 hours at 30-40° C., while stirring, until a free NH₂- group can no longer be detected. The formed urea derivative is precipitated as sodium salt, filtered and dried. It corresponds to the formula

by the 4-nitrobenzoylchloride, behave similarly. The 4-amino-4'-hydroxy-1:1'-azobenzene-3'-carboxylic acid can also be replaced for example by the 4-amino-4'-hydroxy-5'-methyl-1:1'-azobenzene-3'-carboxylic acid, and there may thus be obtained, for instance, a dyestuff of the formula

Example 2

37.6 parts of 4'-(4''-amino)-benzoylamino-1:1'-azobenzene-4-hydroxy-3-carboxylic acid are dissolved in 3000 parts of water with 33.7 parts of 4'-amino-1:1'-azobenzene-4-hydroxy-3-carboxy-2'-sulfonic acid with addition of sodium carbonate until the reaction is distinctly alkaline,

represents an orange powder and dyes cotton in a feebly alkaline bath mixed with a copper salt solution from copper sulfate and sodium tartrate, reddish yellow tints which are fast to washing.

Similar dyestuffs are formed when replacing the 4-(4''-amino)-benzoylamino-1:1'-azoben-

zene-4-hydroxy-3-carboxylic acid by the 4-(4''-amino)-benzoylamino-1:1'-azobenzene-4-hydroxy-5-methyl-3-carboxylic acid, or the 4'-amino-1:1'-azobenzene-2'-methyl-5'-methoxy-4-hydroxy-3-carboxylic acid by the 4'-amino-1:1'-azobenzene-2'-methyl-5'-methoxy-2-hydroxy-3-carboxylic acid. Such a product corresponds for example to the formula

and the whole is treated with phosgene for 20 hours at 30-40° C., while stirring, until a free NH₂- group can no longer be detected. The formed urea derivative is precipitated as sodium salt, filtered and dried. It corresponds to the formula

represents a yellow powder and dyes cotton in a feebly alkaline bath mixed with a copper salt solution from copper sulfate and sodium tartrate, greenish yellow tints which are fast to washing.

Here, too, the 4'-(4''-amino)-benzoylamino-1:1'-azobenzene-4-hydroxy-3-carboxylic acid or the 4'-amino-1:1'-azobenzene-4-hydroxy-3-carboxy-2'-sulfonic acid can be replaced by such compounds in the manufacture of which 1-hydroxy-5-methylbenzene-2-carboxylic acid or

2-hydroxybenzene-1-carboxylic acid are dissolved in 3000 parts of water with 25.7 parts of 4-amino-4'-hydroxy-1:1'-azobenzene-3'-carboxylic acid with addition of sodium carbonate until the reaction is distinctly alkaline, and the whole is treated with phosgene for 20 hours at 30-40° C., while stirring, until a free NH₂- group can no longer be detected. The formed urea derivative is precipitated as sodium salt, filtered and dried. It corresponds to the formula

Example 4

47.1 parts of the aminoazo-dyestuff obtained by saponifying the acetyl group of the monoazo-dyestuff from diazotized 1-(4'-aminobenzoyl)-amino-4-acetylaminobenzene-2-sulfonic acid and

1-hydroxy-6-methylbenzene-2-carboxylic acid has been used instead of 1-hydroxybenzene-2-carboxylic acid.

Example 3

37.6 parts of 4'-(4''-amino)-benzoylamino-1:1'-azobenzene-4-hydroxy-3-carboxylic acid are

2-hydroxybenzene-1-carboxylic acid are dissolved in 3000 parts of water with 25.7 parts of 4-amino-4'-hydroxy-1:1'-azobenzene-3'-carboxylic acid with addition of sodium carbonate until the reaction is distinctly alkaline, and the whole is treated with phosgene for 20 hours at 30-40° C., while stirring, until a free NH₂- group can no longer be detected. The formed urea derivative is precipitated as sodium salt, filtered and dried. It corresponds to the formula

represents a yellow brown powder and dyes cotton in a feebly alkaline bath mixed with a copper salt solution from copper sulfate and sodium tartrate, yellow tints which are fast to washing.

Here, too, the starting products can be replaced by such products in the manufacture of which 1-hydroxy-5-methyl- or 1-hydroxy-6-methylben-

zen-2-carboxylic acid has been used instead of 1-hydroxybenzene-2-carboxylic acid.

Example 5

27.2 parts of 4-(4'-aminobenzoyl)-amino-1-hydroxybenzene-2-carboxylic acid are diazotized in usual manner in 200 parts of water at 5° C. with 6.9 parts of sodium nitrite and 25 parts of concentrated hydrochloric acid, and the diazonium salt thus obtained is coupled with 10.7 parts of 1-amino-3-methylbenzene dissolved in 10 parts of concentrated hydrochloric acid and 200 parts of water. The formed monoazo-dyestuff is heated to 80° C. and separated as sodium salt.

39 parts of the separated product are dissolved in 3000 parts of water with 38.1 parts of 4'-amino-1:1'-azobenzene-2'-methyl-5'-methoxy-4-hydroxy-3-carboxy-5-sulfonic acid with addition of sodium carbonate until the reaction is distinctly alkaline, and the whole is treated with phosgene for 30 hours at 30-40° C., while stirring; until a free NH₂- group can no longer be detected. The urea derivative is precipitated as sodium salt, filtered and dried. It corresponds to the formula

represents a brown powder and dyes cotton in a feebly alkaline bath mixed with a copper salt solution from copper sulfate and sodium tartrate, reddish yellow tints which are fast to washing.

Similar dyestuffs are obtained when replacing the 1-amino-3-methylbenzene by the 1-aminobenzene or the 1-amino-2:5-dimethylbenzene. When

the 1-aminobenzene is used, it should be applied in the form of its ω -methanesulfonic acid and the ω -methanesulfonic acid is split off in known manner after coupling is complete. Moreover, the 4'-amino-1:1'-azobenzene-2'-methyl-5'-methoxy-4-hydroxy-3-carboxy-5-sulfonic acid can be replaced by the 4'-amino-1:1'-azobenzene-2'-methyl-5'-methoxy-2-hydroxy-3-carboxy-5-sulfonic acid, the 4'-amino-1:1'-azobenzene-2:5-dimethyl-4-hydroxy-3-carboxy-5-sulfonic acid, the 4'-amino-1:1'-azobenzene-2':5'-dimethyl-4-hydroxy-3-carboxy-5-sulfonic acid or the 4'-amino-1:1'-azobenzene-4-hydroxy-3-carboxy-5-sulfonic acid, dyestuffs which behave similarly being thus also obtained. Finally, the 4-(4'-aminobenzoyl)-

amino-1-hydroxybenzene-2-carboxylic acid can be replaced by the 4-(3'-aminobenzoyl)-amino-1-hydroxybenzene-2-carboxylic acid. Such a dyestuff corresponds for example to the formula

Example 6

27.2 parts of 1-(4'-aminobenzoyl)-amino-4-hydroxybenzene-3-carboxylic acid are diazotized in usual manner at 5° C. with 6.9 parts of sodium nitrite and 25 parts of concentrated hydrochloric acid, and the diazonium salt thus obtained is coupled with 10.7 parts of 1-amino-3-methylbenzene dissolved in 10 parts of concentrated hydrochloric acid and 200 parts of water. The formed monoazo-dyestuff is heated to 80° C. and separated as sodium salt.

39 parts of the separated product are dissolved in 3000 parts of water with 18.8 parts of 1:4-diaminobenzene-2-sulfonic acid with addition of sodium carbonate until the reaction is distinctly alkaline, and the whole is treated with phosgene for 20 hours at 30-40° C., while stirring, until only one free NH₂- group can be detected. The formed urea is dissolved with caustic soda solution and diazotized at 5-10° C. with addition of 6.9 parts of sodium nitrite and 25 parts of concentrated hydrochloric acid. The precipitated diazonium salt is filtered and coupled at 0° C.

35 with 13.8 parts of 2-hydroxybenzoic acid dissolved in 200 parts of water with 4 parts of sodium hydroxide and 30 parts of sodium carbonate. The dyestuff which has been formed is precipitated as sodium salt, filtered and dried. It corresponds to the formula

45 represents a brown powder and dyes cotton in a feebly alkaline bath mixed with a copper salt solution from copper sulfate and sodium tartrate, reddish yellow tints which are fast to washing.

50 The sulfo group can also be displaced to another part of the molecule. When starting for instance in the first paragraph of this example from the 1-(4'-aminobenzoyl)-amino-4-hydroxybenzene-3-carboxylic acid-5-sulfonic acid, and replacing the operations described in the 2nd paragraph of this example by a linkage with the 4-amino-4'-hydroxy-1:1'-azobenzene-3'-carboxylic acid by means of phosgene, there is obtained a product of the formula

which dyes cotton yellow tints, the wet fastness properties of which are improved by treatment with agents yielding copper.

and wherein neither the radical R₁ nor the radical R₂ contains the sulfonic group, which dyestuffs are yellow to brown powders dyeing the vegetable fiber yellow tints, the wet fastness properties of which are improved by after-treatment with agents yielding copper.

3. The mono-sulfonic acids of the asymmetrical urea-like disazo-dyestuffs of the general formula

wherein R₁, R₂, R₃ and R₄ each stands for an aromatic nucleus of the benzene series, the $-\text{N}=\text{N}-$ group and the

group standing in 1:4-position to one another, R₁ and R₄ each containing an OH— group and a carboxyl group in ortho-position to this OH— group and R₂ containing the sulfonic group, which dyestuffs are yellow to brown powders dyeing the vegetable fiber yellow tints, the wet fastness properties of which are improved by after-treatment with agents yielding copper.
